UNITED STATES PATENT OFFICE.

WILLIAM R. HEBER, OF BERKELEY, CALIFORNIA, ASSIGNOR TO PRINCETON KNITTING MILLS, OF RICHMOND, CALIFORNIA, A CORPORATION OF CALIFORNIA.

ADJUSTABLE BATHING-SUIT.

1,254,593.

Specification of Letters Patent. Patented Jan. 22, 1918.

Application filed April 23, 1917. Serial No. 163,829.

To all whom it may concern:

Be it known that I, WILLIAM R. HEBER, a citizen of the United States, residing at Berkeley, in the county of Alameda and State of California, have invented new and useful Improvements in Adjustable Bathing-Suits, of which the following is a specification.

This invention relates particularly to improvements in bathing suits, and especially that class of suits which is termed a single-piece bathing suit.

It consists in the combination with the body and leg portions of such a suit, of means for adjusting the suit to larger or smaller persons.

It also comprises details of construction which will be more fully explained by reference to the accompanying drawings, in which—

Figure 1 is a front view of the suit and its attachment.

Fig. 2 is a separate fragment, showing the adjustable attachment.

In bathing establishments where it is customary to furnish suits to all comers, it is often difficult to find a suit which exactly fits the bather; some suits being too large and others too small. It is the object of my invention to provide means for fitting a single size of bathing suit to all the different figures to which it may be applied.

As shown in the drawings, A is the body portion of the suit and B the leg portions, these being all woven in one piece, and they may have an apron or outer portion C extending from the waist downwardly. The suit is sleeveless and the upper portion is formed with separate front and back members α — α' and has bands 2 extended from the upper edge of the back member adapted to pass over the shoulders after the suit has been drawn onto the body of the wearer. The side openings between the front and back members form armholes. If the person having the suit has a long body the tendency will be to make the suit too short in the shoulders on account of the close fit of the crotch seam, and if, on the other hand, the person is short, the opposite effect will result and the suit will be loose and sloppy in every direction.

In order to overcome this difficulty, I have shown straps 3 connected with the shoulder portion, and the front member of the body

A is formed with slots 4 into which the ends of these straps may be passed and concealed. A plurality of buttonholes 5 is formed in the straps 3 and buttons 6 are placed upon the front of the garment, over which one or the other of these buttonholes may be fixed while the remainder of the strap 3 is passed into the slot 4 and concealed within the front of the garment. Buttons 6^a are fixed within the front member α to which the inner ends of the strap 3 are secured. It is thus very easy to fit a garment of this description.

The depth of the armholes is such that the front and back may be turned down in opposite directions and the body piece drawn up over the body with the crotch seam of the part B fitting closely. The back and front are then brought together in their respective positions and the straps 3 brought over the shoulders and passed downward at the front until the particular buttonhole, which insures a good fit of the garment, can be attached to the button 6. The remainder of the strap, as before described, then passes into the slotted opening 4 within the garment and is secured to the interior button 6^a, thus leaving it hidden from view and without exposing any loose ends to become entangled.

Having thus described my invention, what I claim and desire to secure by Letters Patent is—

1. A bathing suit composed of a body piece and integral trunks, said body piece being open at the top to form a head opening and armholes, shoulder straps connected to the back and having button holes at their free end parts, the front face of the body piece having slots formed below the top of the body piece to receive the free end parts of the straps so as to enable the latter to be engaged to the rear of the front face of the body piece and be concealed thereby, and buttons on the front face of the body piece above and adjacent to the slots to receive the buttonholes of the straps to thereby hold the free ends of the latter in said slots of the front of the body piece.

2. A bathing suit composed of a body piece and integral trunks, said body piece being open at the top to form a head opening and armholes, shoulder straps connected to the back and having button holes at their free end parts, the front face of the body piece having slots formed below the top of

the body piece to receive the free end parts of the straps so as to enable the latter to be engaged to the rear of the front face of the body piece and be concealed thereby, buttons 5 on the front face of the body piece above and adjacent to the slots to receive the button holes of the straps to thereby hold the free ends of the latter in said slots of the front of the body piece, and buttons on the rear 10 face of the body piece below the slots to re-

ceive one of the buttonholes of the parts of the straps which extend on the rear face of the front of the body piece.

In testimony whereof I have hereunto set my hand in the presence of two subscribing 15 witnesses.

WILLIAM R. HEBER.
